ROCKET DECELERATED MINE

Donald Q. Brumbaugh, Hyattsville, Md., assignor to the United States of America as represented by the Secretary of the Navy

Application October 15, 1954, Serial No. 462,635

3 Claims. (Cl. 102—7)

(Granted under Title 35, U. S. Code (1952), sec. 266)

The invention described herein may be manufactured and used by or for the Government of the United States of America for governmental purposes without the payment of any royalties thereon or therefor.

The present invention relates to a device for decelerating a mine and more particularly to a device for reducing the forward velocity of a mine whereby the mine may enter the water without damage thereto or to the delicate mechanism contained therein when launched at high or low altitudes from a fast moving aircraft.

More specifically, the invention relates to a decelerating device for use in an aerial launched mine in which the decelerating force is produced by a rocket motor mounted in the nose of the mine and which includes fuzes means operated as the mine is dropped from the aircraft in flight for initiating the rocket motor when the mine is a predetermined distance from the surface of a body of water thereby to reduce the velocity of the mine prior to entrance of the mine into the water.

The parachute method heretofore used for decelerating a mine during a mine planting operation has not proven entirely satisfactory particularly when the mine was released from high altitudes and a direct opening chute was employed for the reasons that the chute caused the mine to drift off course due to the various aerodynamic forces acting thereon and thus preventing accurate planting of the mine in the desired area and the delayed opening type parachute method required complicated control devices and equipment which at times proved unreliable.

The present invention overcomes the disadvantages heretofore encountered by providing a new and improved rocket decelerating device which is devoid of cumbersome parachute packs and fragile control devices whereby the mine may be accurately planted in the desired area and the forward motion of the mine is invariably retarded as the mine approaches the surface of the body of water.

An object of the invention is to provide a new and improved rocket decelerating device for an aerial launched mine.

Another object of the invention is the provision of a rocket decelerating device which may be readily installed in a conventional marine mine for reducing the forward velocity of the mine after the mine is launched from a fast moving aircraft.

A further object of the invention is to provide a mine deceleration device in which the decelerating force is produced by a rocket motor actuated as the mine approaches the surface of a body of water after the mine is dropped from an aircraft in flight.

A further object of the invention is to provide a mine deceleration device constructed and arranged to reduce the velocity of the mine in predetermined time delayed relation with respect to impact of the mine with the surface of a body of water thereby to prevent damage to the mine and the mine control mechanism contained therein as the mine enters the water.

A still further object of the invention is the provision of a rocket deceleration device for an aerial launched marine

2

mine wherein a discharge jet of a rocket motor operated in time delayed relation with respect to the release of the mine from an aircraft in flight thereby to reduce the forward velocity of the mine prior to entrance of the mine into a body of water.

Other objects and many of the attendant advantages of this invention will be readily appreciated as the same becomes better understood by reference to the following detailed description when considered in connection with the accompanying drawing wherein:

Fig. 1 is an elevational view of a mine partially broken away and partially in section illustrating a preferred embodiment of the present invention attached to a marine mine;

Fig. 2 is a view similar to Fig. 1 illustrating an alternate arrangement of the device of Fig. 1; and

Fig. 3 is a fragmentary sectional view of a mine illustrating another alternate arrangement of the device of Fig. 1.

Referring now to the drawing wherein like characters of reference are used to designate like parts throughout the several views and more particularly to Fig. 1 thereof, the numeral 10 generally indicates the mine. The mine comprises a casing 11 having a stabilizing assembly 12 secured to one end and a centrally disposed tubular member 13 formed on the other end thereof enclosed by the mine casing 11 and providing a well 14 within the leading end or nose of the mine casing.

The deceleration device consists essentially of a rocket motor 15 and a fuze 16, as illustrated, the aforesaid elements are disposed within the well or recess 14 and arranged along the longitudinal axis of the mine casing.

The motor 15 comprises a tube 17 secured to the mine casing 11 as at 18 by threaded engagement therewith and having propellant charge 19 therein. A nozzle 20 is disposed within the tube 17 at the nose end of the mine and a squib 21 and igniter 22 is disposed within the tube and arranged at one end of the propellant charge 19. It will be noted that the fuze 16 is releasably mounted in the forward end of the tube 17 by a pair of resilient elements 23 disposed about the fuze casing and in frictional engagement with the tube 17, the fuze being electrically connected to the squib 21 by a pair of conductors 24.

The fuze 16 may be a well known conventional VT type fuze such, for example, as the type which is actuated by reflections of a radio signal transmitted therefrom and from the water or land when the mine is a predetermined distance from the surface thereof. The fuze, however, is rendered operable as the arming wire 25 is withdrawn therefrom, withdrawal of the arming wire occurring as the mine is released from an aircraft and falls away therefrom. When this occurs, the fuze is in a condition to be operated in response to water reflections thereby to supply an electrical firing impulse to the squib 21 by way of conductors 24. Moreover, the fuze 16 is constructed and arranged to initiate the rocket motor when the mine is a predetermined distance from the surface of the body of water such, for example, as from 500 to 1000 feet.

Upon firing of the squib 21 in the aforesaid manner, the igniter 22 is ignited which, in turn, ignites the propellant charge 19. It will be understood that when the propellant 19 is ignited, the fuze 16 is forcibly ejected from the motor tube 17 by the force of the jet developed and discharged through nozzle 20. Thus as the rocket motor operates the resulting action creates a substantial backward thrust to slow the forward velocity of the mine sufficiently to permit the mine to enter the water without damage thereto.

If desired, a pair of slip connectors may be provided on the pair of conductors 24 respectively at the squib end of the motor to detachably secure the conductors thereto whereby the conductors may be carried along with the

fuze as the fuze is forcibly ejected from the motor tube 17 in the aforesaid manner. Furthermore, suitable insulating material 30 is disposed between the tube 17 and tubular element 13 thereby to heat insulate the motor from the main charge 26 whereupon firing of the main charge by the heat developed as the propellant is ignited and burns is prevented.

Referring now to Fig. 2, the arrangement shown thereon is particularly adapted for use in mine planting operations at low altitudes such, for example, as at 200 feet and comprises a fuze generally indicated by the reference character 27. It will be noted that the mine, rocket motor and fuze retaining elements are identical to the structure shown in Fig. 1 and thus like reference characters are employed to designate such like parts.

The fuze 27 illustrated on Fig. 2 is a percussion fired and delayed type fuze and comprises a casing 28 releasably held in the nose end of the mine by the resilient elements 23. A delay element 29 and flash charge 31 is disposed within one end of the casing 28, the flash charge having one end of a quick burning pyrotechnic fuze 32 connected thereto, the other end of the fuze being connected to the squib 21. A spring actuated firing pin 33 is releasably held in an initial safe position by the arming wire 25, the wire being withdrawn to release the firing pin in the manner heretofore set forth. When this occurs, the firing pin is forcibly driven into firing engagement with the delay element 29 by the spring 33' whereupon the delay element is fired. After a predetermined period of time has elapsed the delay element fires the flash charge 31 which ignites the quick burning fuze 32 thereby firing the squib 21. The squib ignites the igniter 22 which ignites the propellant 19 whereupon the fuze 27 is forcibly ejected from the motor tube 17 and thus the rocket motor will operate in the same manner as heretofore set forth to retard the forward motion of the mine.

In the arrangement of Fig. 3, the fuze is generally indicated by the reference character 34 and comprises casing 35 releasably secured within the motor tube 17 in like manner to fuzes 16 and 27. The fuze 34 is preferably a mechanical delay type fuze which is rendered operable as the arming wire 25 is withdrawn therefrom and may include either a suitable clock mechanism of any well known type such, for example, as the type of clock mechanism employed in an automatic electric toaster or motor means having a reduction gear arrangement for actuating the switch 36 from a normally open position to a closed position in predetermined time delayed relation with respect to the release of the mine from the aircraft by movement of the switch actuating rod 39 as the arming wire 25 is withdrawn. The switch comprises a pair of contacts 36 and 37 normally engaging a sleeve 38 mounted on the switch actuating rod 39 and composed of any insulating material suitable for the purpose. By this arrangement, the switch is normally open and will remain open until the rod 39 is moved axially toward the trailing end of the mine by the aforesaid mechanisms. It will be understood that as the rod 39 is moved, contacts 36-37 are brought into engagement with the rod which is composed of conducting material. When this occurs, the firing circuit 41 connected to the squib 21 and including contacts 36-37 and a battery B is rendered effective thereby to fire the squib which ignites the igniter 22 and thus the rocket motor is set in operation whereupon the resulting action forcibly ejects the fuze 34 from tube 17 and creates a substantial backward thrust to slow the forward velocity of the mine.

Briefly stated in summary, the present invention contemplates the provision of a new and improved deceleration device for an aerial planted marine mine for reducing the forward velocity of the mine after the mine has

been released from the aircraft and a predetermined period of time before the mine enters a body of water.

Obviously many modifications and variations of the present invention are possible in the light of the above teachings. It is therefore to be understood that within the scope of the appended claims the invention may be practiced otherwise than as specifically described.

What is claimed as new and desired to be secured by Letters Patent of the United States is:

- 10 1. A decelerating device for a mine adapted to be dropped from an aircraft in flight comprising, in combination, a mine casing having a centrally disposed well formed therein and opening in the nose portion thereof, a rocket motor disposed within said well, a fuze disposed within said well, means including a normally open firing circuit connected to said motor and fuze for igniting said rocket motor as said firing circuit is closed, normally open switch means carried by said fuze and included in said firing circuit for closing said firing circuit, a movable rod having a contact element carried thereby for closing said switch means as the rod is moved longitudinally from an initial locked position to a moved position, an arming wire releasably connected to said rod for locking the rod in said initial position until the arming wire is disconnected therefrom, and a time delay actuating mechanism connected to said rod for moving the rod to said moved position when a predetermined period of time has elapsed after the arming wire has been disconnected.
- 20 2. A device for decelerating the forward velocity of an aerial launched mine as the mine approaches the surface of a body of water comprising, in combination, a mine casing having an axially disposed wall integral with said casing and forming a well within the casing, a container disposed within said well in threaded engagement with said casing and in uniform spaced relation with respect to said wall, a rocket motor having a propellant charge disposed within said container, an igniter arranged within said container for igniting said propellant charge as the igniter is ignited, a percussive fuze disposed within and releasably sealed in one end of the well and adapted to be forcibly ejected therefrom by the products of combustion of the propellant charge as the charge is ignited, a pair of mutually spaced annular grooves formed in said wall, a pair of complementary grooves formed in said fuze, a pair of mutually spaced annular resilient elements disposed within said grooves in the wall and fuze respectively for releasably sealing said fuze within the well, a firing pin carried by said fuze, means for actuating said firing pin to a firing position as the mine is released from an aircraft in flight, a pyrotechnic delay element carried by said fuze and ignited by said firing pin, a pyrotechnic flash charge carried by said delay element and ignited thereby, a quick burning elongated pyrotechnic fuze having one end connected to said flash charge and the other end thereof connected to said igniter and ignited by said flash charge for igniting said igniter when a predetermined period of time corresponding to said delay has elapsed thereby to ignite said propellant charge when the mine is a predetermined distance above the surface of the water, an explosive charge disposed within said casing in engagement with said wall, and heat insulating material disposed between said wall and container and completely filling the space therebetween for preventing firing of said explosive charge by the heat developed by said delay element, flash charge, pyrotechnic fuze and the propellant charge during ignition and buring thereof.
- 30 3. A device for decelerating the forward velocity of an aerial launched mine as the mine approaches the surface of a body of water comprising, in combination, a mine casing having an axially disposed wall integral with said casing and forming a well within the casing, a container disposed within said well in threaded engagement with said wall and in uniform spaced relation with respect to

said wall, a rocket motor disposed within said container, an igniter arranged within the container for igniting said rocket motor, an electrical fuze disposed within and releasably sealed in one end of the well and adapted to be forcibly ejected therefrom by the products of combustion of the motor as the motor is ignited, means including a pair of mutually spaced resilient elements carried by said fuze in engagement with said wall for releasably sealing the fuze in said well, a source of electrical energy arranged within the fuze, a normally open firing circuit connected to said igniter and said source for igniting said igniter as said circuit is closed, a rod composed of electrical conducting material arranged within said fuze and movable axially from an initial position to a moved position, a sleeve composed of insulating material mounted on said rod, a pair of contacts included in said firing circuit normally in engagement with said sleeve for closing the firing circuit as the sleeve is moved by said

rod an amount sufficiently to move the contacts out of engagement with the sleeve and into engagement with said rod, and a clock time delay actuating mechanism arranged within said fuze, for moving said rod from said initial position to said moved position a predetermined period of time after the mine has been dropped from an aircraft in flight.
